D526,044 S * 8/2006 Torichigai et al. D23/209
7,323,040 B2 * 1/2008 Poschmann 96/9

(75) Inventors: **Yusuke Okawa**, Toshima-ku (JP);
Kazuhiko Noto, Toshima-ku (JP);
Yasuyuki Okuno, Amagasaki (JP)

* cited by examiner

(73) Assignee: **Hitachi Plant Technologies, Ltd.**,
Toshima-ku (JP)

Primary Examiner — Robin V Webster

(**) Term: **14 Years**

(74) *Attorney, Agent, or Firm* — Wenderoth, Lind & Ponack,
L.P.

(21) Appl. No.: **29/347,653**

(57) **CLAIM**

(22) Filed: **Mar. 30, 2010**

The ornamental design for an immersion flat filter membrane element, as shown and described.

(30) **Foreign Application Priority Data**

Nov. 12, 2009 (JP) 2009-026499
(51) **LOC (9) Cl.** **23-01**
(52) **U.S. Cl.** **D23/209**

DESCRIPTION

U.S. PATENT DOCUMENTS
4,956,085 A * 9/1990 Kopf 210/231
D324,720 S * 3/1992 Kopf D23/209

FIG. 1 is a front view of the present invention;
FIG. 2 is a rear view of the present invention;
FIG. 3 is a left side view of the present invention;
FIG. 4 is a right side view of the present invention;
FIG. 5 is a top view of the present invention;
FIG. 6 is a bottom view of the present invention; and,
FIG. 7 is a cross-sectional view taken along line 7-7 of FIG. 1.
